WEAVING LOOM CLOTH BEAM SUPPORT

Jaime Picanol, Zandberg, Zillebeke-lez-Ypres,
BelgiumApplication September 27, 1951, Serial No. 248,610
In Belgium April 27, 1951

5 Claims. (Cl. 139—308)

1

The present invention relates to weaving looms and more particularly to the cloth beam support means. The cloth beam is normally carried by supports movable vertically or substantially vertically, generally through the intervention of rack devices.

These supports involve a problem which, although not influencing the weaving technique or the qualities of the loom itself, raises an economic question which is of considerable interest. If we consider that the cloth beams can attain a diameter up to 500 mm. and that such diameters are more and more frequent due to subsequent requirements in the finishing, printing and other operations, if we also consider that these beams must be moved into the alleys which separate the rows of weaving looms, it will be found necessary to provide said alleys with a free passage of 600 mm. minimum width. However, the present known supports of the cloth beams are so designed as to permit only a progressive vertical lowering of said beams and consequently these beams protrude more and more into the alleys as their diameter increases. The distance between two looms in the same row must, therefore, be substantially greater than said minimum of 600 mm. as the large space occupied by the two beams disposed in front of each other must be allowed for. It is important to provide means for diminishing this space in order to increase considerably the number of looms in a room of a given surface. If we consider, for instance, a room of 900 looms, with 30 rows of 30 looms each, it will be easy to understand that, by gaining 150 mm. per loom, about 15% of the occupied floor space will be saved and consequently it will be possible to increase by 15% the number of looms in the same weaving room, without changing the working space for the operators. This reduction of the space occupied by the cloth beams is relatively considerable.

The object of the invention is a new device permitting the reduction of the space occupied by the cloth beams at least in the proportions indicated, without affecting in any way the safety conditions during the winding of the cloth and the facilities to remove the rolls and to proceed with the various operations which are customary.

The device object of the invention is essentially characterised by the provision of at least two curved racks or toothed sectors which are guided in slides, fixed at both sides of the loom, each a rack meshing with a toothed pinion fixed on a rack common axle, surrounded by coil springs; a helical gear is freely mounted on said axle and meshes with a worm, the shaft of which is provided with a handwheel; said coil springs extend on both sides of said helical gear and are, at one extremity, secured to said axle and, at their

2

other extremity, secured to the hub of said helical gear. The shaft of the beam on which the cloth is wound bears at its two extremities on bearing bushes disposed at the upper end of the racks.

5 The racks are held by the toothed pinions, which are in turn held by the coil springs. When the diameter and therefore the weight of the cloth beam increases, the force exerted on the racks increases and provokes the rotation of the toothed pinions and the progressive tension of the springs. From this it results that the elastic reaction of these springs increases with the increasing weight of the cloth beam. Thus, a practically constant counterbalance is maintained, the initial pressure being maintained between the cloth beam and the driving beam. When the cloth beam has reached its final diameter, the stresses exerted by the springs on the racks are reduced to zero by operating the handwheel which causes the rotation of the helical wheel and of its hub; upon turning, the latter releases the tension of the springs.

20 This mechanism is extremely simple and has also the advantage of allowing, at any time, adjustment of the tension of the springs, that is, adjustment of the force which is opposed to the fall of the racks under the weight of the cloth beam.

25 It is possible to vary the form and shape of the different elements which have been described and which characterise essentially the support of the invention, to suit any particular type of loom.

30 For illustration only and without any limitative character, an embodiment is described hereafter with reference to the annexed drawings, in which:

35 Figures 1 and 2 are schematic end elevations of weaving looms showing the space occupied by the cloth beams when carried respectively by the known supports and by the device according to the present invention;

40 Figures 3 and 4 are schematic lateral and front elevations of the essential elements of the device according to the present invention;

45 Figures 5 and 6 represent, respectively side and front elevations of a preferred embodiment.

45 The device, according to the present invention, comprises at least two racks 1, 2 in the form of a circular arc, the convex part of which is toothed. These racks are guided into their respective slide 3, 4 which have a U-shaped cross-section and which are rigidly secured to the respective side-frames 5, 6 of the loom by the respective pairs of braces 7, 8 and 9, 10, and by bolts 11, 12, 13, 14 respectively. The racks form, at their upper ends, cradles 15, 16 respectively, for removably receiving the ends 17, 18 of the shaft of the cloth beam 19 on which is wound the cloth T produced on the weaving loom.

Toothed pinions 20, 21 keyed to a common axle 22 mesh with their respective curved racks 1, 2.

In the embodiment shown in Figures 3 and 4, the two ends of axle 22 are resting in bearings which are located in the respective projections 23, 24 integrally depending from their respective guides 3, 4.

On the middle section of the axle 22 is freely mounted a helical wheel 25, the hub of which is extended at both sides by sleeves 26, 27 each provided with at least one teat, respectively 28, 29.

Said helical wheel 25 and its lateral sleeves 26, 27 are freely rotatable on said axle 22. Furthermore, two collars 30, 31 are keyed to the axle 22 in spaced relationship with the free ends of sleeves 26, 27 of the hub of the helical wheel 25. Tightening screws 32, 33 secure said collars to the axle 22 and the collars are each provided with a teat 34, 35. The axle 22 is partially surrounded by two coil springs 36, 37, the first one being attached at one end to the teat 28 of the sleeve 26, and at the other end to the teat 34 of the collar 30, the second spring being attached at one end to the teat 29 of the sleeve 27, and at the other end to the teat 35 of the collar 31. The helical wheel 25 meshes with a worm 38, the shaft 39 of which is resting in a stationary support 40 and is provided with an operating handwheel 41.

Suppose that the loom is operating normally and that a certain amount of cloth is already wound on the cloth beam 19, the weight of this beam is pressing down on the two racks 1, 2, which causes the respective toothed pinions 20, 21 to rotate and drive the common axle 22 and the collars 30, 31. Whilst rotating, these collars are tensioning the coil springs 36, 37, one end of said springs is kept immobilised on the hub of the helical wheel 25 which remains stationary. As the diameter of the cloth beam increases, and consequently its weight, the coil springs 36, 37 become progressively stressed, resulting in a progressive increase of their elastic reaction with the increasing diameter of the cloth beam. The use of the proper springs, and an intermediary element between them and the cloth beam produces a practically constant counterbalance, that is to say, a practically constant pressure between the cloth beam 19 and the driving beam A is maintained.

When the cloth beam has attained a suitable diameter and before removing it from its supporting racks 1, 2 it will, of course, be necessary to neutralize the reactive tension of the springs 36, 37 which have a permanent tendency to throw the racks 1, 2 upwards. For that purpose it will be sufficient to turn the handle 41 to cause the corresponding rotation of the helical wheel 25 and of its lateral extension sleeves 26, 27. This rotation can be such that it will effect the release of the springs. When these latter are completely released, the support of the cloth beam will be free and said beam can be normally removed. When a new beam is placed with its ends 17, 18 on the cradles 15, 16 of the respective racks 1, 2, it will be sufficient to turn the handwheel 41 in the reverse direction to obtain a tension of the springs 36, 37 which, when their elastic tension is sufficient, will drive the axle 22, the toothed pinions 20, 21, the racks 1, 2 and the bobbin or cloth beam 19. The latter can thus be brought in correct position, according to the prevailing requirements. When said cloth beam 19 is in position, it is still possible to regulate the pressure exerted by the cloth beam against the drive beam A by further turning the handwheel 41.

With supports, as just described, it is possible to reduce considerably the obstruction of the alleys by the cloth beams and consequently to reduce also the width of said alleys. If we examine the Figure 1, representing schematically two looms 42, 43 provided with straight, vertical support racks 44, it is found that the obstruction of the alley 45 which separates said looms is considerable. If we take, for example, an alley of 600 mm. width, the obstruction would soon be such that the width L of the free passage would be at a maximum of 300 mm., so that said alley 45 should have an initial width of at least 900 mm. If comparatively we examine Figure 2, in which are represented two looms 46, 47 provided with the device of the invention with toothed sectors 1, we notice that the space occupied by the cloth beam 19 is substantially reduced, this space being at least one half lesser than the space needed with the known supports of Figure 1.

While a preferred embodiment according to the present invention has been illustrated and described, it is understood that various modifications may be resorted to without departing from the spirit and scope of the appended claims.

I claim:

1. In a support for the cloth beam of a weaving loom, two curved racks placed at both sides of the cloth beam and supporting said cloth beam; means to guide longitudinally said racks, an axle substantially parallel to the cloth beam, placed under the latter, toothed pinions keyed to said axle and meshing with said racks; resilient means connected to said axle whereby said means become progressively stressed with the increasing weight of said cloth beam.

2. In a support according to claim 1, said curved racks removably supporting the shaft of said cloth beams; said guide means including two slides secured to the frame of said loom; a gear wheel freely rotatable on said axle; a worm meshing with said gear wheel; a handwheel for said worm and a coil spring surrounding said axle and secured at one end to said gear wheel and at the other end to said axle.

3. In a support according to claim 2, said racks being in the form of a circular arc with teeth disposed along the longitudinal and convex edge thereof, said slides having a U-shaped cross-section.

4. In a support according to claim 2, said curved racks having their upper end provided with a cradle to removably receive the ends of the shaft of the cloth beam, said racks being able to slide in their respective guides under the weight of the cloth beam thereby causing rotation of the toothed pinions with which they are meshing.

5. In a support according to claim 2, said gear wheel having depending sleeves at both sides thereof, collars secured to said axle and spaced from said sleeves, and coil springs surrounding said axle and each secured to one of said sleeves at one end and to the associated collar at the other end.

JAIME PICANOL.
